Filed Aug. 5, 1974, Ser. No. 494,952

Term of patent 14 years

Int. Cl. D7—03

U.S. Cl. D7—148

FIG. 1 is a side elevational view of a cheese slicer or the like showing my new design, the side opposite being a mirror image thereof;

FIG. 2 is a top plan view thereof;

FIG. 3 is a bottom plan view thereof;

FIG. 4 is a front elevational view thereof;

FIG. 5 is a rear elevational view thereof; and

FIG. 6 is an enlarged fragmentary cross-sectional view of the cutting blade taken along line 6—6 of FIG. 1.

I claim:

The ornamental design for a cheese slicer or the like, substantially as shown and described.
